UNITED STATES PATENT OFFICE.

JOHN H. VAN RIPER, OF CHELSEA, MICHIGAN.

IMPROVEMENT IN HARNESS-PADS.

Specification forming part of Letters Patent No. 125,101, dated March 26, 1872.

To whom it may concern:

Be it known that I, JOHN H. VAN RIPER, of Chelsea, in the county of Washtenaw and State of Michigan, have invented a new and useful Improvement in Harness-Pads; and I do declare that the following is a true and accurate description thereof, reference being had to the accompanying drawing and to the letters of reference marked thereon and being a part of this specification, in which—

Figure 1 is a perspective view of my improved pad; Fig. 2 is a central transverse section of the same; Fig. 3 is a cross-section at *xx*; and Fig. 4 is a perspective view of the check-hook detached from the tree.

Similar letters of reference indicate corresponding parts in the several figures.

The object of this invention is to provide an improved pad for harnesses, having all the advantages of what is known as the "coach-pad" with the cheapness of the common or "soft" pad, which will possess sufficient flexibility to conform to the back of the horse, and which will be easy to repair. The invention consists in the peculiar construction of the metallic tree and check-hook, and in combination therewith the remaining parts of the pad, as more fully hereinafter set forth.

In the drawing, A represents my improved tree, preferably made of malleable cast-iron, consisting of two flat plates joined together, as shown, with a loop, *a*, for the back-strap projecting rearward from the point of juncture, which is flattened and strengthened by the addition of ribs *b b c*, the latter being recessed to receive the front end of the check-hook B, which is secured by a bolt, *d*, inserted from the top and riveted under the tree, so that the hook can easily be replaced if broken. The lower end of each plate is curved to receive the end

of the top layer, which in common pads extends entirely over the pad. C are the cushions, and D the housing of a pad of ordinary construction, over which is laid the fold E, extending entirely over the pads. F is the layer, which extends or terminates under the extremities of the tree-plates, and is only stitched to the fold where exposed. *ee* are two screws passing through the tree-plates, the fold, housing, and into the cushions, into nuts *ff*, which bind the whole firmly together. The terrets G also screw into nuts *g* which are placed within the cushions. *h* are fancy saddle-screws engaging with nuts *h'*, one at each end of the pad, within the cushion, to keep the pad ends in place.

By this arrangement I save ten inches of leather in the length of the layer, and twenty-two inches of stitching, which, with the saving of time in the manufacture of the pad, will pay for the metallic tree; so that, in other words, I am enabled to make a coach-pad at the cost of the common or soft-pad.

That part of the pad which is below the ends of the tree-plates is sufficiently flexible to conform to the shape of the horse's back.

I do not claim, broadly, the invention of a metallic pad-tree, as such have long been used, but differing materially from mine in construction and application; but—

What I claim as new, and desire to secure by Letters Patent, is—

In combination with the pad-tree A the cushions C, fold E, and layer-ends F, the whole being secured together by the screws *ee h* and nuts *ff* and *h'*, as and for the purpose set forth.

JOHN H. VAN RIPER.
